ROUNABOUT

Carl L. Hannas, St. Paul, Alberta, Canada

Filed Sept. 22, 1960, Ser. No. 62,238

Term of patent 7 years

(Cl. D34—5)

FIG. 1

FIG. 2

FIGURE 1 is an elevational view of the roundabout showing my new design, and

FIGURE 2 is a side view looking at the right hand side of FIGURE 1.

The present application is a continuation-in-part of prior application D. 59,646, filed March 7, 1960, now abandoned.

I claim:

The ornamental design for a roundabout, as shown and described.
